Henry Moore

Inventor:
Paul Riebe,
By Robert Burns, Atty.

Fig. 4.

UNITED STATES PATENT OFFICE.

PAUL RIEBE, OF CHICAGO, ILLINOIS.

ADJUSTABLE GUIDE-PLATE GUARD.

1,077,432.

Specification of Letters Patent.

Patented Nov. 4, 1913.

Application filed March 24, 1913. Serial No. 756,344.

To all whom it may concern:

Be it known that I, PAUL RIEBE, a citizen of the United States of America, and a resident of Chicago, in the county of Cook, 5 State of Illinois, have invented certain new and useful Improvements in Adjustable Guide-Plate Guards, of which the following is a specification.

This invention relates to the bed and cylinder type of printing presses, and more especially to the feed guides against which the sheets of paper abut to attain proper register in the printing operation. And the present improvement has for its object to 15 provide a simple and effective structural formation and combination of parts in a feed guide, whereby a very accurate register is attained regardless of the thickness of paper used, or any wavy or other irregular 20 nature of such paper, all as will hereinafter more fully appear.

In the accompanying drawings:—Figure 1 is a side elevation with parts in section, illustrating the general arrangement of the 25 present improvement as adapted to the front guide of a printing press. Fig. 2, is a rear elevation of the same. Fig. 3, is a horizontal section on line $x-x$, Fig. 1. Fig. 4, is a similar view, on line $x'-x'$, Fig. 1.

30 Similar reference numerals indicate like parts in the several views.

Referring to the drawings, 1 represents the usual rock shaft of the press, upon which the front guides are mounted for 35 transverse adjustment as required, and said shaft receives the usual intermittent rocking motion in unison with the other mechanisms of the press.

2 is the usual socket member of a front 40 guide. Said socket member is formed with the usual clamping collar 3, by which it is secured in a transverse adjustable manner on the aforesaid rock shaft 1, and with a rearwardly extending tubular arm 4, for 45 the hereinafter described stem of the front guide plate.

5 is the feed board of the press disposed to the rear of the rock shaft 1, and carrying the usual transversely adjustable guide 50 rests 6 for the front guide plates above referred to.

7 is a front guide plate of the usual triangular form and fixedly secured to the rear end of a carrying stem 8, which in turn is

carried in a longitudinally adjustable manner by the tubular arm 4, of the socket member 2, aforesaid. The lower end of the plate 7 is formed with a pair of depending marginal prongs 9, adapted to straddle the front bar or finger of the guard rest 6, to hold 60 the parts against independent lateral motion, and at the same time prevent a slippage of the paper sheet under the guide plate 7. Intermediate of the prongs 9, the lower end of the guide plate 7 is formed 65 with a pair of separated recesses or notches 10, for the reception of the free ends of the elastic guide plate guard hereinafter described.

11 is the elastic feed plate guard, preferably formed of resilient sheet metal, and comprising an orificed vertical attaching portion 12, by which it is secured to the rear end of the carrying stem 8, aforesaid; an intermediate curved or loop shaped portion 75 13, and a free lower portion 14, which is normally inclined to the finger of a guard rest 6, to provide a rearwardly flaring guide throat between the parts, as shown in Fig. 1. Said lower portion 14, as well as the 80 adjacent part of the loop portion 13, are bifurcated to form a pair of counterpart elastic prongs as shown, with the free ends of said prongs engaging in the separated notches 10 in the lower end of the guide 85 plate 7. In the present improvement the said prongs are provided with lateral extensions 15 adapted to provide increased bearing surfaces adjacent to the guide plate, and with a view to more effectively remove 90 any curvature, etc., in the margin of the sheet of paper being fed against the guide plate, and in consequence attain more perfect register.

16 is an upright adjusting shaft disposed 95 within the loop shape elastic guard 11 aforesaid, and formed with upper and lower screw-threaded portions, which are preferably right and left handed respectively, as shown, and separated by a central enlargement 17, adapted to afford means for the manual rotation of the shaft as required. The upper portion of the shaft 16 has abutment against the approximately rigid curved portion 13 of the guard 11, and in the particular construction shown in the drawings passes through a longitudinally elongated slot 18, in the guard 11 aforesaid, and is 100 105

capable of movement along said slot in the varied adjustments of the parts hereinafter described.

19 is a nut engaging the lower screw-threaded end of the shaft 16, and secured to the elastic prongs of the lower portion 14 of the guard aforesaid, by a series of attaching feet 20, as shown.

21 is a nut engaging the upper screw-threaded portion of the shaft 16, and disposed beneath the upper part of the intermediate loop portion 13 of the guard aforesaid. Said nut is provided with a side projection 22, which engages in the elongated slot 18 to prevent independent rotation of said nut.

23 is a bearing washer surrounding the upper portion of the shaft 16, and having bearing upon the upper surface of the guard 11 aforesaid, as shown in Fig. 1. It is preferable to make the bearing surfaces of the nut 21 and washer 23 of the curved form shown, with a view to attain uniform bearings in the varied adjustments of the parts.

24 is a clamping nut engaging the upper end of the shaft 16, and having bearing upon the washer 23, and adapted to clamp the parts in position, after an adjustment has been effected.

30 While I have shown and described my invention as applied to the front guide of a press, it is within the scope of my invention to apply the same to the companion side guides carried at one side of the feed board.

35 In the practical operation of the present structure, a turning of the screw-threaded shaft 16, in one direction or the other, is adapted to either increase or diminish the size of the rearwardly flaring throat between the free lower portion 14 of the guard, and the finger of the guide rest 6, to suit different thicknesses of paper used on the press.

45 By a longitudinal shifting of the upper end of the shaft 16, in one direction or the other in the elongated slot 18 of the guard aforesaid, and either alone, or in conjunction with a rotation of said shaft 16, the rearward flare of the aforesaid throat can be increased or diminished to meet the varied practical requirements in an attainment accurate register of the sheets or paper, and due to varied thicknesses, wavy nature, etc., of the paper used.

55 In the present improvement the elastic feed plate guard and its adjusting means constitute a self-contained portion or unit of the press structure, and are capable of ready attachment and detachment as a whole, in that its sole means of attachment is the holding nut which secures the guide plate 7 in place upon the stem 8 of the press structure. Such construction is accordingly economical in manufacture and convenient in actual use.

Having thus fully described my said invention what I claim as new and desire to secure by Letters Patent, is:—

1. In a feed guide for printing presses, the combination of a guide plate, an open loop shape guard having a fixed portion secured against the upper portion of the guide plate and an adjustable free portion associated with the lower end of said guide plate, and an adjusting means disposed within said loop shape guard and attached at its respective ends to said guard to provide a self-contained structure. 70

2. In a feed guide for printing presses, the combination of a guide plate, an open loop shape guard associated with said plate, and means disposed within said loop shape guard for varying the size thereof, the same comprising an upright screw-threaded shaft, and nuts associated with said shaft and with the upper and lower portions of said loop shaped guard. 80

3. In a feed guide for printing presses, the combination of a guide plate, an open loop shape guard associated with said plate, and means disposed within said loop shape guard for varying the size thereof, the same comprising an upright screw-threaded shaft, and nuts associated with said shaft and with the upper and lower portions of said loop shaped guard, said guard having an elongated slot at the top for the passage and longitudinal adjustment of the upper end of the aforesaid shaft. 90

4. In a feed guide for printing presses, the combination of a guide plate, an open loop shape guard associated with said plate, and means disposed within said loop shape guard for varying the size thereof, the same comprising an upright right and left hand screw-threaded shaft, a nut secured to the lower free portion of said guard and having engagement with the lower portion of said shaft, a nut bearing beneath the upper portion of said guard and having engagement with the upper portion of said shaft, and a clamping nut engaging said shaft outside the guard aforesaid. 100

5. In a feed guide for printing presses, the combination of a guide plate, an open loop shape guard associated with said plate, and means disposed within said loop shape guard for varying the size thereof, the same comprising an upright right and left hand screw-threaded shaft, a nut secured to the lower free portion of said guard and having engagement with the lower portion of said shaft, a nut bearing beneath the upper portion of said guard and having engagement with the upper portion of said shaft, and a clamping nut engaging said shaft outside the guard aforesaid, said guard having an elongated slot at the top for the passage and longitudinal adjustment of the aforesaid shaft. 110

6.. In a feed guide for printing presses, the combination of a guide plate, an open loop shape guard having a fixed portion secured against the upper portion of the 5 guide plate and an adjustable free portion associated with the lower end of said guide plate, said adjustable free portion having a bifurcated form to provide a pair of elastic prongs with each prong formed with an 10 outward lateral extension in coacting rela-
tion to the lower edge of the guide plate, and means associated with said guard for adjusting the free portion thereof.

Signed at Chicago, Illinois, this 20th day of March, 1913.

PAUL RIEBE.
